HAT HEAD-SIZE MEASURING-MACHINE

Frank Marriott, Ferguson, and Walter E. Hyatt,
St. Louis, Mo.

Application September 14, 1933, Serial No. 639,340

5 Claims. (Cl. 33—179)

This invention relates to a certain new and useful improvement in machines for measuring the head-size of hats and has for its chief object the provision of a machine of the type and for 5 the purpose stated which is simple and inexpensive in structure, which may be economically manufactured, which may be easily and conveniently manipulated, and which is precise, accurate, and efficient in the performance of its 10 intended functions.

And with the above and other objects in view, our invention resides in the novel features of form, construction, arrangement, and combination of parts presently described and pointed out 15 in the claims.

In the accompanying drawing,—

Figure 1 is a plan view of a machine of our invention for measuring the head-size of a hat; and

20 Figure 2 is a sectional view of the machine taken approximately on the line 2—2, Figure 1. Referring now more in detail and by reference characters to the drawing, which illustrates a practical embodiment of our invention, the machine 25 comprises a base A in the form preferably of a metallic or other suitable rigid flat plate preferably, as shown, of rectangular contour with rounded corners and marginally flanged, as at 1, the flange 1 having suitable feet-providing enlargements, as at 2, for resting on a table, desk, work-bench, or the like.

Suitably within its area, plate A is provided with a bearing 3 for accommodating a vertically disposed stub-shaft 4, pinned to which, as at 5, 35 for concentric rotatory movement on and over the plate A, is a drum B having preferably the skeleton formation best seen in Figure 2.

Fixed to, and upstanding from, the plate A in adjacency to and upon opposite sides of the 40 drum B, are suitable posts 6, 6', and C designates a steel-band or other way-providing member, which is edgewise disposed on the plate A with one end attached to the post 6. From the post 6, the band C extends embracingly about the 45 periphery of drum B and is suitably attached adjacent its opposite end, as shown, to the other post 6', and to the projecting band end-portion 7, a flexible preferably steel ribbon or tape D is adjacent one end permanently fixed, as at 8, the 50 one end-portion 9 of ribbon or tape D being presented intermediate the posts 6, 6', toward the drum B for co-operation therewith in the formation of a mouth for the tape-way provided intermediate the drum B and the fixed band C.

55 The tape D, which may be of any suitable

length, is convoluted and windable about the periphery of drum B and at its other end is fixed, as at 10, to the periphery thereof, for purposes presently appearing.

Adjacent a margin, the plate A is cut-away or 60 apertured, as at 11, in the provision of a sight-opening for visually presenting or exposing a head-size scale or head-size graduations 12 marginally carried in an annular series on a disk E suitably mounted, as at 13, on the shaft 4 for 65 rotatory movement under the plate A.

Adjacent a margin, the plate A is suitably formed with a second bearing, as at 14, for accommodating for rotation a vertically disposed stub-shaft 15, to the upper end of which is fixed 70 a preferably knurled manipulating member or button 16. And suitably fixed, as at 17, on the shaft 15 for rotatory movement under the plate A, is a driving-sprocket-wheel 18 connected, as by a chain 19, with a driven-sprocket-wheel 20 75 suitably fixed, as at 21, on the shaft 4 under, and also suitably fixed, as at 22, to the disk E, and it will be evident that, on manipulation of the button 16, the drum B and disk E will be simultaneously rotarily actuated relatively to 80 the plate A, the tape D wound upon, or unwound from, the drum B or, as may be said, annularly expanded or contracted relatively to the drum B, and the corresponding head-size of the hat being measured visually displayed at the sight-opening 11.

It is, of course, to be understood that, when the tape D is in fully wound or contracted condition, the disk E will display at the sight-opening 11 the smallest head-size measurement of 90 the particular machine.

Now, in use and operation, the hat whose head-size is to be measured is disposed upon the plate A and over the drum B and contracted tape D. The button or knob 16 is thereupon manipulated 95 to expandingly unwind the tape D, as indicated in dot-dash lines, Figure 1, until the same firmly and snugly engages the wall of the crown of the so disposed hat, the disk E thereupon displaying at the opening 11 the proper, accurate and precise measurement of the head-opening of the particular hat. Thereupon, the button 16 is reversely manipulated and the tape D correspondingly contracted to permit convenient removal of the measured hat.

100 The machine is simple in structure, is conveniently usable, and is precise and efficient in the performance of its intended functions.

105 It is to be understood that changes in the form, construction, arrangement, and combination of 110

the several parts of the machine may be made and substituted for those herein shown and described without departing from the nature and principle of our invention.

5 Having thus described our invention, what we claim and desire to secure by Letters Patent is,—

10 1. A hat head-size measuring machine comprising, in combination, a base, a drum mounted for rotatory movement in a horizontal plane on, and having its peripheral wall vertically disposed to, the base, a convoluted flexible tape edgewise disposed to the base having one end attached to the peripheral wall of the drum and its other end fixed on the base for annular expansion and contraction about the drum, and means for rotarily actuating the drum for annularly expanding and contracting the tape.

15 2. A hat head-size measuring machine comprising, in combination, a base, a drum mounted for rotatory movement in a horizontal plane on, and having its peripheral wall vertically disposed to, the base, posts fixed to, and upstanding from, the base upon opposite sides of the drum, a way-forming band edgewise presented to the base and fixed to said posts for partially surrounding the peripheral wall of the drum, said band having an end-portion projecting intermediate the posts, a measuring-tape also edgewise disposed to the base fixed at an end to the peripheral wall of the drum and at its other end to the projecting end-portion of the band for annular expansion and contraction about the drum and band, and means for rotarily actuating the drum for annularly expanding and contracting the tape.

20 3. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 25 edgewise disposed to the base having one end fixed to the peripheral wall of the drum and its other end on the base for annular expansion and

30 4. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 35 edgewise disposed to the base having one end fixed to the peripheral wall of the drum and its other end on the base for annular expansion and

40 5. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 45 edgewise disposed to the base having one end fixed to the peripheral wall of the drum and its other end on the base for annular expansion and

50 6. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 55 edgewise disposed to the base having one end fixed to the peripheral wall of the drum and its other end on the base for annular expansion and

60 7. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 65 edgewise disposed to the base having one end fixed to the peripheral wall of the drum and its other end on the base for annular expansion and

70 8. A hat head-size measuring machine comprising, in combination, a base having a sight-opening, a drum mounted for rotatory movement in a horizontal plane upon, and having its peripheral wall vertically disposed to, the base, a scale-disc mounted for rotatory movement in a horizontal plane on the under face of the base for visually displaying a carried scale-graduation at the sight-opening, a convoluted flexible tape 75 edgewise disposed to the base having one end fixed to the peripheral wall of the drum and its other end on the base for annular expansion and

contraction about the drum, and means for simultaneously rotating the drum and disc for expanding or contracting the band and displaying a corresponding scale-graduation at the sight-opening.

80 4. A hat head-size measuring machine comprising, in combination, a base provided with a sight-opening, a vertically disposed stub-shaft mounted for rotation on the base, a drum fixed on said shaft for rotatory movement in a horizontal plane over, and having its peripheral wall vertically disposed to, the base, a scale-disc fixed to the shaft for rotatory movement in a horizontal plane under the base for visually displaying a carried scale-graduation at said sight-opening, a convoluted flexible tape edgewise disposed to the base having one end fixed to the peripheral wall of the drum and its other end on the base for annular expansion and contraction about the drum, and means for simultaneously rotating the drum and disc for expanding or contracting the band and displaying a corresponding scale-graduation at the sight-opening.

85 5. A hat head-size measuring machine comprising, in combination, a base provided with a sight-opening, a vertically disposed stub-shaft mounted for rotation on the base, a drum fixed on said shaft for rotatory movement over the base, a scale-disc fixed to the shaft for rotatory movement under the base for visually displaying a carried scale-graduation at said sight-opening, a convoluted flexible tape having one end fixed to the periphery of the drum and its other end to the base for annular expansion and contraction about the drum, and means for simultaneously rotating the drum and disc for expanding or contracting the band and displaying a corresponding scale-graduation at the sight-opening, said means comprising a second vertically disposed stub-shaft mounted for rotation on the base, sprocket-wheels on said shafts, a chain connecting said wheels, and a manipulating button on the second shaft.
